UNITED STATES PATENT OFFICE.

JAMES MURPHY, OF BRIDGEPORT, CONNECTICUT.

POLICE-NIPPER.

1,102,943.

Specification of Letters Patent.

Patented July 7, 1914.

Application filed January 17, 1914. Serial No. 812,683.

To all whom it may concern:

Be it known that I, JAMES MURPHY, citizen of the United States, and resident of Bridgeport, in the county of Fairfield and 5 State of Connecticut, have invented certain new and useful Improvements in Police-Nippers, of which the following is a specification.

This invention relates to new and useful 10 improvements in nippers such as are employed by policemen and other officers while on duty to grasp and lead a prisoner.

The object of the invention is to generally improve and simplify the construction of 15 devices of this sort and to especially provide a nipper which may be conveniently operated; to form it so that it may be readily opened by engaging a trigger with the finger of the hand that grasps the nipper.

20 With the above and other objects in view my invention resides and consists in the novel construction and arrangement of parts shown upon the accompanying sheet of drawings forming a part of this specification 25 and upon which,

Figure 1 shows a top plan view of my improved nipper complete, the same being indicated in a closed position. Fig. 2 is a similar top plan view of the nipper open, 30 and in a position to grasp the wrist of the prisoner. Fig. 3 is a bottom side edge view of the nipper shown in Fig. 1. Fig. 4 shows a sectional elevation of the nipper taken on line 4—4 of Fig. 2 and Fig. 5 is a vertical cross section taken on line 5—5 of Fig. 1 showing the means for locking the jaws of the nipper together.

As will be noted my improved nipper 40 briefly includes a pair of jaws which are connected together and normally retained in a closed position by means of a spring. It also includes a pair of handles that are pivotally connected to the jaws and serves to support the nipper while in use and likewise to lock and hold the jaws in both an 45 open and closed position.

Referring in detail to the characters of reference marked upon the drawings 6 represents the upper or main jaw member and 50 whose outer portion is bowed to form substantially one-half of a circle. The intermediate portion of the shank 7 of this jaw is straight, while the extreme end portion is enlarged to form a part of a knuckle to 55 which the corresponding knuckle end of the co-acting jaw 8 is pivotally connected. One

end of a spring 9 is secured to the upper or main jaw by means of a screw 10 as shown, while the other end is disposed against the under side of the lower or operating jaw 8. A trigger 11 is secured to the lower or operating jaw and is provided with an extended rack 12 that passes through the said jaw and also through a suitable opening 13 in the shanks 7 of the two jaws 6 60 and 8. The opposite side portions of this extended rack 12 is provided with a series of teeth 14 as shown in Fig. 5 that are engaged by the inner edges of the shanks 15 and 16 connected to the operating handles as will 65 later be explained. The screw 10 which secures the spring 9 to the shank 7 of the upper jaw 6 also serves to pivotally connect the two shanks 15 and 16 of the handles 17 and 18 to the shank of the upper jaw 6 and 70 75 in a way to permit of a limited swinging movement of the two said shanks and handles. The amount of this movement is limited by the size of the holes 19 through the said shanks and through which the before mentioned rack 12 passes. These two handle shanks are formed of sheet metal and lie close together as shown in the drawings and thus serve to operate in close proximity to each other. One of them serves 80 85 to engage one side of the rack 12, while the other one serves to engage the other side of the rack in a like manner. This engagement is for the purpose of holding the lower jaw of the nipper in an open position, 90 after it has been so set by drawing down upon the before mentioned trigger. After being set open the said jaw and rack are quickly released by loosening up on the handles of the nipper which are drawn outward 95 by the spring 20 seated in the knuckle of the nipper and intermediate of the two shank portions of the handles. The normal position of the nipper is closed as shown in Figs. 1 and 3, while the open position shown 100 in Fig. 2 is only maintained by holding the handles together as shown in Fig. 4. This opening is effected against the action of the spring 20 which serves to cause the edges 105 110 115 120 125 130 135 140 145 150 155 160 165 170 175 180 185 190 195 200 205 210 215 220 225 230 235 of the prisoner is grasped, whereupon the handles are sufficiently released to allow the jaws to close around the arm of the prisoner. Then the handles are again tightly grasped in order to hold the jaws in a locked position.

Having thus described my invention what I claim and desire to secure by Letters Patent is:

- 10 1. A police nipper of the class described, the same comprising a pair of jaws pivotally connected together, a spring for normally holding the said jaws in a closed position, a rack secured to one of the said jaws, a pair 15 of handles connected to the other jaw and having means to engage the said rack and hold said jaw in an open position against the action of the spring.
2. A police nipper of the class described, 20 the same comprising a pair of jaws pivotally connected together, a spring for holding the same in a closed position, a pair of handles pivotally connected to one of the said jaw members, a trigger secured to the other jaw

for operating the same, a rack secured to one 25 jaw and adapted to engage the other jaw in a way to hold the jaws in an open position when the handles are clasped.

3. In a police nipper of the class described, the combination of a pair of jaws 30 pivotally connected together, a spring for normally holding the same in a closed position, a trigger and rack secured to one of said jaws, said rack extending through the shank of the other of said jaws, a pair of handles pivotally connected to one of the said jaws and having their free edge portions in position to engage the teeth of the rack in a manner to lock the same in position.

40 Signed at Bridgeport in the county of Fairfield and State of Connecticut this 14th day of January A. D., 1914.

JAMES MURPHY.
